DESIGN FOR A TEXTILE FABRIC OR SIMILAR ARTICLE

Lester Conrad, New York, N. Y.

Application November 23, 1935, Serial No. 59,721

Term of patent 3½ years

To all whom it may concern:

Be it known that I, Lester Conrad, a citizen of the United States, residing in the city of New York, county of New York, and State of New York, whose post-office address is 32 Thomas Street, city of New York, county of New York, and State of New York, have invented a new, original, and ornamental Design for a Textile Fabric or Similar Article, of which the following is a specification, reference being had to the accompanying drawing, forming a part thereof.

The figure is a plan view of a textile fabric embodying my new design.

The main features of the design consist of bars of heavy fancy yarn woven into a fancy weave of block effect produced by different colors, the bars being slightly raised above the surface of the fabric.

I claim:

The ornamental design for a textile fabric or similar article as shown and described.

In testimony whereof I have signed this specification.

LESTER CONRAD.
